BUCKLE

Nils Linus Tannersjö, Boden, Sweden, assignor
to Gösta Wännström, Boden, SwedenApplication April 22, 1949, Serial No. 89,029
In Sweden June 4, 1946

1 Claim. (Cl. 24—180)

1

The present invention relates to a buckle for straps provided with holes and comprising a buckle-frame bent to form a guide for the strap with a front plate, two side plates and two back flanges, a transverse bolt at one end of said buckle-frame for fastening one end of the strap and locking means cooperating with the holes in the strap.

One object of the invention is to provide a locking device which is introduced in the holes of the strap automatically by means of spring action. Another object of the invention is to provide a pressure grip on the locking device within the buckle-frame, which can easily be operated by a finger in order to release the locking device but is protected from being operated inadvertently. A still further object of the invention is to obtain a spring operated buckle of small dimensions and without any projecting parts.

The invention will be more clearly understood from the following description and the accompanying drawing, in which:

Fig. 1 is a plan view from below of one form of the buckle according to the invention and a portion of the strap fastened thereto.

Fig. 2 is a section on lines II—II in Figure 1.

Fig. 3 is a similar section with the locking device in a released position.

In the drawing 1 designates a leather strap provided with a single row of holes 2, but it is obvious that also more rows may be used. At the one end 3 the leather strap is formed to a flap 4 of reduced width, which flap is folded over a transverse bolt 5 and secured thereto by means of rivets 6. A plate 7 of sheet metal is bent along the longitudinal edges in such a way that a front plate 8 two side walls 9 and two back flanges 10 are formed to guide the strap. The bolt 5 is at first bent to a U-form, and the shanks are thereafter bent at a right angle and inserted from within into holes in the flanges 10 and secured thereto by clinching. The middle portion of the bolt 5 is located outside the buckle frame in such a way that the other end 11 of the strap can be introduced between the front plate 8 and the bolt 5 with the fixed end 3 of the strap. A locking device or tooth plate 13 is tiltingly mounted on a transverse pin 12. The tooth plate may be formed of sheet iron, in which transverse chutes are pressed in the extension of each other but from different sides in such a way that the pin 12 may be introduced in the chutes for tiltingly mounting of the tooth plate. The ends of the pin are bent at a right angle and inserted from within into holes in the flanges 10 to which the pin is secured by clinching.

In the portion of the plate 13 located between

the pin 12 and the bolt 5 is pressed a chute 14, which has an extension bent towards the front plate and formed to a locking tooth 15 for cooperation with the holes 2 in the strap. The tooth 15 is normally pressed towards the front plate by means of a spring 16 made of piano-wire. The ends of the spring are bent at a right angle and rest against the flanges 10, and the middle portion of the spring is secured to the chute 14 in any suitable way, i. e. by means of a pin through the plate or by welding. The tension of the spring is so directed that the middle portion of the spring endeavours to force the tooth from the position shown in Fig. 3 to the position according to Fig. 2. The opposite portion of the tooth plate forms a pressure grip, which by a finger can be pressed towards the strap in order to release the locking tooth 15.

Although only one form of the invention is illustrated in the drawing it is obvious that different modifications are possible without departing from the scope thereof.

I claim:

A buckle for connecting two end portions of a belt, comprising a buckle-frame bent to form a guide for a strap with a front plate forming a plane front surface of the buckle, two plane side walls and two back flanges, a U-shaped transverse bolt at one end of said buckle-frame secured to the inside of said flanges and extending beyond the ends of said side walls for fastening one end of the belt, a locking tooth plate located within said buckle-frame and covered by said front plate, a transverse pin fastened to the inside of said flanges, for pivotally mounting of said tooth plate, one end of said tooth plate being located between said bolt and said pin and having at least one tooth bent towards said front plate, a transverse spring acting upon said tooth plate to introduce said tooth into holes in the free end of the strap when this end is inserted in the buckle-frame guide at the end opposite to said bolt, and the other end of said tooth plate forming a pressure grip for lifting the tooth against the action of said spring.
